UNITED STATES PATENT OFFICE.

LEX P. BOOE, OF CHANUTE, KANSAS.

CORN-PLANTER.

SPECIFICATION forming part of Letters Patent No. 692,232, dated February 4, 1902.

Application filed October 10, 1901. Serial No. 78,251. (No model.)

To all whom it may concern:

Be it known that I, LEX P. BOOE, a citizen of the United States, residing at Chanute, in the county of Neosho and State of Kansas, 5 have invented a new and useful Corn-Planter, of which the following is a specification.

My invention relates to an improvement in corn-planters, particularly with reference to the construction of the shoe for opening the 10 furrows in which the seeds are deposited and the arrangement of the disks carried by the shoe, which widen the furrows and operate in advance of the shoe to cut and remove trash out of the path thereof.

15 My invention consists in the peculiar construction and combination of devices herein-after fully set forth and claimed.

In the accompanying drawings, Figure 1 is a perspective view of a corn-planter shoe and 20 disks constructed in accordance with my invention. Fig. 2 is a horizontal longitudinal sectional view of the same. Fig. 3 is a vertical transverse sectional view of the same. Fig. 4 is a partial elevation of the same, the 25 near disk being removed.

In the embodiment of my invention my improved furrow-opening shoe 1, which is provided with the curved front edge 2, has a pair of rearwardly-extending and rearwardly-diverging wings 3, between which is secured 30 the lower end of the seed-spout 4. Said seed-spout has shoulders 4^a on its sides, which bear on the wings 3. The lower edge 5 of the shoe extends some distance below the lower side 35 of the wings 3, and on the upper side of the front portion of the shoe in advance of the seed-spout is formed a vertical shouldered extension 6, thereby considerably increasing the depth or vertical extension of the shoe.

40 Relatively the front portion of the shoe in advance of the seed-spout is short as compared with the shoes of this class now in common use. The draft-bar 7 is formed separately from the shoe, and the rear end of the 45 said draft-bar lies against one side of the vertical extension of the shoe and is secured thereto by one of the bolts 8, which are employed to secure a pair of blocks 9 to opposite sides of the said vertical extension of the shoe.

50 The said blocks are formed with overhanging flanges 10 at their upper inner sides, which flanges bear on the upper edge of the vertical

extension of the shoe. Each of the said blocks 9 is formed on its outer side at its central portion with an extended boss 11. Through the 55 centers of the said blocks extend openings 12, which are obliquely disposed and diverge forwardly, and in the said openings are secured the headed inner portions of a pair of forwardly-diverging spindles 13. On the said 60 spindles are journaled revoluble concavo-convex disks 14, which are formed with bearing sleeves 15 on their front or outer sides. Collars 16 are secured on the outer ends of the spindles 13, either by set-screws 17, as here 65 shown, or by any other suitable means. It will be observed by reference to the drawings, more particularly to Figs. 2 and 4 thereof, that the front cutting edges of the disks 14 extend in advance of the front edge 2 of the shoe 1, 70 and thereby the said disks serve to cut trash in advance of the shoe and to clear the same away from the path of the shoe when the machine is in operation.

Having thus described my invention, I 75 claim—

1. In a corn-planter, a furrow-opening shoe extending in advance of the seed-spout and revoluble disks carried by said shoe, the said disks being so disposed that the front, cutting edges thereof are in advance of the front edge of the said shoe, for the purpose set forth, substantially as described.

2. A furrow-opening shoe having a vertical extension on its front portion and rearwardly-diverging wings, in combination with a seed-spout, in rear of said extension, having its lower end disposed between the wings and shouldered on its sides to bear upon them, substantially as described.

3. In a corn-planter, a shoe having a vertical extension on the upper side of its front portion, in advance of the seed-spout, blocks secured on opposite sides of said vertical extension, and having overhanging flanges to 95 bear on the upper edge thereof and revoluble disks carried by said blocks, substantially as described.

4. In a corn-planter, a shoe having a vertical extension on the upper side of its front portion, in advance of the seed-spout, blocks secured on opposite sides of said vertical extension, revoluble disks carried by said blocks and a draft-bar having its rear end secured

to the said shoe between the vertical extension thereof and one of said blocks, substantially as described.

5. A furrow-opening shoe having a vertical extension on its front portion and rearwardly diverging wings, in combination with a seed-spout in rear of said extension and having its lower end disposed between the wings, substantially as described.

10. 6. In combination with a shoe having a vertical extension on the upper side of its front portion, a seed-spout in rear of said vertical

extension and revoluble disks carried by said shoe and having their front, cutting edges in advance of the front edge of the shoe, substantially as described. 15

In testimony that I claim the foregoing as my own I have hereto affixed my signature in the presence of two witnesses.

LEX P. BOOE.
